COMBINED FLASHLIGHT AND EMERGENCY LIGHT

William Brunnhoelzl, Deep River, Conn.

Application August 16, 1950, Serial No. 179,847

11 Claims. (Cl. 340—321)

1

This invention relates to combined flashlights and emergency lights, i. e., lights which may be utilized either as an ordinary flashlight or as a danger-signal light.

It is an object of the present invention to provide a combination flash-and-emergency light which in its normal use as a flashlight offers no indication whatever of its dual character as a flash-and-emergency light, and which may, on simple manipulation thereof and without any interchange or addition of parts, be instantly converted into an emergency light which is of a different shape and considerably larger size than the light-orifice in the flashlight and is in its illumination effect in striking contrast therewith, so that the emergency light will draw maximum attention and be clearly perceptible as such from a considerable distance in the dark or even in broad daylight.

It is another object of the present invention to provide a combination flash-and-emergency light of this type which in its normal use as a flashlight has the typical form and appearance of a conventional flashlight.

It is a further object of the present invention to provide a combination flash-and-emergency light of this type which in its use as an emergency light simulates a lighted torch that is especially apt to draw attention and be perceptible as a danger or emergency signal.

It is still another object of the present invention to provide a combination flash-and-emergency light of this type which, when used as an emergency light, will nevertheless function as a flashlight also and emit a beam of incandescent light which may be useful and desirable for different purposes and will in no wise detract from, and may even enhance, the effectiveness of the emergency light.

Other objects and advantages will appear to those skilled in the art from the following, considered in conjunction with the accompanying drawings.

In the accompanying drawings, in which certain modes of carrying out the present invention are shown for illustrative purposes:

Fig. 1 is an elevational view of a combined flash-and-emergency light which embodies the present invention and is shown in its normal form as a flashlight;

Fig. 2 is a view similar to Fig. 1, but showing the light in its alternate form as an emergency light;

Fig. 3 is a longitudinal section through the combined flash-and-emergency light in its normal form as a flashlight;

2

Fig. 4 is a fragmentary longitudinal section through the combined flash-and-emergency light in its alternate form as an emergency light; and Figs. 5 to 7 are sections taken on the lines 5—5, 6—6 and 7—7, respectively, of Fig. 3.

Referring to the drawings, and more particularly to Figs. 1 to 3 thereof, the reference numeral 10 designates a combined flash-and-emergency light which in its normal use as a flashlight preferably has the form and appearance of a conventional flashlight (Fig. 1). Thus, the instant light comprises a casing or receptacle 11 for a battery or batteries B, a socket 12 for a light bulb b, a removable cap 13 for the open head-end 14 of the battery-casing 11, a light-reflector 15, and switch-means 16 for turning the light on and off. The casing 11 is, in the present instance, also open at its rear end 17 for the insertion of the batteries B, and is normally closed therewith by a removable, preferably threaded cover 18. The socket 12, which forms one terminal for the light bulb b, may be secured at 19 to an insulating-support 20 which may, in turn, be secured at 21 to a mounting-bracket 22 on the inside of the casing 11 (Figs. 3 and 6). The other terminal for the light bulb b may be formed by a contact-pin 23 which extends through the insulating-support 20 and may be secured at 24 to a mounting-strap 25 on the support 20 (see also Figs. 6 and 7). The cap 13, which in the form shown is of the screw-on type, is provided with an orifice 26 for the outward passage of light from the bulb b. As usual, the orifice 26 in the cap 13 is closed by a transparent cover 27 which may conveniently be held in place in the cap 13 by a split-ring 28. The light-reflector 15, which may be parabolic for the forward reflection of the light rays from the bulb b in the form of a concentrated beam, is provided with a central aperture 29 through which the socket 12 normally extends (Fig. 3). The light-reflector 15 may, for its attachment to the cap 13, be interposed with its peripheral flange 30 between the transparent cover 27 and the holding-ring 28. The switch-means 16 comprises, in the present instance, a sliding switch-actuator 31 and a contact-strip 32 of which the latter may be in permanent electrical contact with the preferably metallic battery-casing 11, and may be shifted into and from contact with the base 12' of the socket 12 by the switch-actuator 31 (Figs. 4 and 3) to close the open light circuit through the bulb b. The light switch in the instant light is self-evident, and for that reason requires no further description. The light described so far is of conventional

flashlight type and forms no part of the present invention, except insofar as it enters into combination therewith.

The present invention is embodied in the instant light in provisions by means of which the light may readily and instantly be converted from a flashlight into an emergency light, and vice versa. These provisions comprise a collapsible light-tube 35 which in its extended operative condition (Figs. 2 and 4) is adapted to be illuminated by light from the bulb b in order to serve as an emergency light-signal. The light-tube 35 is, in the present instance, of a telescopic type, having interfitting tube sections 36 of transparent, and preferably translucent, plastic or any other suitable material. Preferably, the tube sections 36 are hollow frusto-cones which are extensible into a tube of predetermined length (Figs. 2 and 4), and are securely held in extended operative condition by their frictional engagement with each other without offering undue resistance to their collapse by the user of the light when the emergency light is no longer needed.

The largest tube section 36' is, in the present instance, retained in the open head-end 14 of the battery-casing 11 by a split-ring 37 (Fig. 4). In order that the cap 13 may remain attached to the instant light even when the latter is used as an emergency light (Figs. 2 and 4), the cap 13 is secured to the smallest tube section 36'' and movable therewith to and from the head-end 14 of the battery-casing 11. To this end, the light-reflector 15 has, in this instance, secured thereto in any suitable manner depending prongs 38 (Figs. 4 and 5) which extend along the inner wall surface of the smallest tube section 36'' and are anchored with their outwardly-formed ends 39 in adjacent end-notches 40, respectively, in the tube section 36''. If desired, the prongs 38 may near their anchored ends 39 be re-enforced by a preferably integral ring 41 (Figs. 4 and 5).

In the extended condition of the light-tube 35 (Fig. 4), the largest tube section 36' thereof is held against the holding-ring 37 by a compression-type spring 42 through intermediation of an interposed auxiliary light-reflector 43 which bears with its peripheral flange 44 against the adjacent end of the tube section 36'. The spring 42, which surrounds the socket 12, bears with its inner end against the socket-base 12'.

The auxiliary light-reflector 43 is, in the form of the instant light as an emergency light (Fig. 4), adapted to replace the light-reflector 15 which is then out of light-reflecting relation with the light bulb b. Since the auxiliary light-reflector 43 bears against the tube section 36' within the confines of the battery-casing 11 when the light-tube 35 is extended (Fig. 4), the auxiliary reflector is depthwise of smaller dimension than the other reflector 15 in order to be in similar light-reflecting relation with the bulb b as the latter reflector. The auxiliary light-reflector 43 may, like the reflector 15, be parabolic, or substantially parabolic, so as to reflect at least part of the light rays from the bulb b in a concentrated beam which passes through the extended light-tube 35, the central aperture 29 in the reflector 15 and the orifice 26 in the cap 13. However, the light emanating from the bulb b and the reflected light from the auxiliary reflector 43 brightly illuminate the interior of the extended light-tube 35 which, by virtue of its preferably translucent character, transmits some light to the outside, but primarily appears to an observer, even from a considerable distance, as a brightly illuminated signal lamp.

To stress the emergency character of the illuminated light-tube 35 in its extended condition, the telescopic sections 36 thereof may bear any suitable color or other markings which, when illuminated, are generally associated with danger or an emergency. Since the color "red" is most widely accepted as signifying danger or emergency, the tube sections 36 are preferably of that color.

10 In order to convert the instant light from its normal form as a flashlight (Figs. 1 and 3) into its alternate form as an emergency light, it is merely necessary to unscrew the cap 13 from the battery-casing 11 and draw the former out until the tube sections 36 are in their extended operative condition (Figs. 2 and 4). After the emergency light is no longer needed, the user of the light shifts the projecting cap 13 toward the head-end 14 of the battery-casing 11, thereby collapsing the light-tube 35. On collapsing the light-tube 35 and screwing the cap 13 over the head-end 14 of the battery-casing 11, the reflector 15 is again brought into proper light-reflecting relation with the light bulb b, while the auxiliary reflector 43 is depressed by the collapsed light-tube 35 into the position shown in Fig. 3. On restoring the instant light to its normal form as a flashlight, the collapsed sections 36 of the light-tube 35 will become nested in each other and interposed between the reflectors 15 and 43 in a manner like or similar to that shown in Fig. 3. In reapplying the cap 13 to the head-end 14 of the battery-casing 11, the reflector 15 will also depress the largest tube section 36' deeper into the casing 11 where it may rest on the auxiliary light-reflector 43. However, the holding-ring 37 will remain in place in the head-end 14 of the casing 11 and again hold the tube section 36' against withdrawal from the casing on the next extension of the light-tube 35, as will be readily understood.

45 The instant light 10 is advantageous in several important respects. Thus, the light 10 may, on simple manipulation and without requiring any interchange or addition of parts, be instantly converted from a flashlight into an emergency light, and vice versa. The instant light is in its normal form as a flashlight, without any perceptible indication of its dual character as a flash-and-emergency light, and may in its normal form have the typical appearance of a conventional flashlight. The instant light is in its alternate form as an emergency light especially effective as such in that the extended light-tube 35 is in its illumination effect in striking contrast with that of the flashlight. Thus, the extended light-tube 35 is of an entirely different shape and considerably larger size than the light-orifice in the flashlight. Moreover, the advantageous frusto-conical shape of the tube sections 36 lends to the extended light-tube 35 the appearance of a torch which, when illuminated in the dark or even in broad daylight, is especially apt to draw attention, and by its red color, clearly signifies a danger or emergency signal. Also, the instant light will, when used as an emergency light, nevertheless function as a flashlight also and emit a beam of incandescent light which may be useful for different purposes and will in no wise detract from, and may even enhance, the effectiveness of the emergency light.

55 The invention may be carried out in other specific ways than those herein set forth without departing from the spirit and essential characteristics of the invention, and the present em-

bodiments are, therefore, to be considered in all respects as illustrative and not restrictive, and all changes coming within the meaning and equivalency range of the appended claims are intended to be embraced therein.

I claim:

1. In a combined flash-and-emergency light, the combination of a casing having an opening; a socket for a light bulb in said casing; a cap removably mounted on said casing and having an orifice in alignment with the opening in said casing for the outward passage of light from a bulb in said socket; and a light-permeable tube connected with said cap and said casing, and having provision for permitting said tube to be extended from and retracted into said casing through said opening therein on removing said cap from and mounting it on said casing, respectively, said tube being in its extended condition in illuminating relation with, and forming between the opening in said casing and the orifice in the removed cap a passage for, light from a bulb in said socket, and said tube being marked to signify, when illuminated, an emergency signal, and being in its retracted condition out of the path of light between the opening in said casing and the orifice in said cap.

2. In a combined flash-and-emergency light, the combination of a casing having an opening; a socket for a light bulb in said casing; a cap removably mounted on said casing and having an orifice in alignment with the opening in said casing for the outward passage of light from a bulb in said socket; and a light-permeable collapsible tube secured with its ends to said casing and cap, respectively, and having provision for permitting said tube to be axially extended and contracted on removing said cap from and mounting it on said casing, respectively, said tube being in its extended condition in illuminating relation with, and forming between the opening in said casing and the orifice in the removed cap a passage for, light from a bulb in said socket, and said tube being marked to signify, when illuminated, an emergency signal, and being in its collapsed condition out of the path of light between the opening in said casing and the orifice in said cap.

3. The combination in a combined flash-and-emergency light as set forth in claim 2, in which said tube comprises telescoping tube sections of which the tube sections which are endmost in the tube in the extended condition of the latter are secured to said casing and cap, respectively.

4. The combination in a combined flash-and-emergency light as set forth in claim 2, in which said tube comprises telescoping tube sections of frusto-conical shape so that said tube is extensible to a predetermined length, and the tube sections which are endmost in said tube in the extended condition of the latter are secured to said casing and cap, respectively.

5. In a flashlight, the combination with a tubular battery-casing having an open head-end; a socket for an electric light bulb centrally in said casing adjacent said head-end thereof; and a cap removably mounted on, and having a light-orifice in alignment with, the head-end of said casing; of a light-permeable tube comprising telescoping tube sections of which the cross-sectionally largest and smallest tube sections are secured in the head-end of said casing and to said cap, respectively, substantially coaxially of said casing and substantially concentrically with the orifice in said cap, respectively, so that said tube will

be extended from and contracted into the head-end of said casing on removing said cap from and mounting it on the head-end of said casing, respectively, said tube being in its extended condition in illuminating relation with a bulb in said socket, and said tube sections being marked to signify, when illuminated, an emergency signal.

6. The combination in a flashlight as set forth in claim 5, in which said tube sections are frusto-conical so that they are extensible into a tube of predetermined length.

7. In a flashlight, the combination with a tubular battery-casing having an open head-end; a socket for an electric light bulb centrally in said casing adjacent said head-end thereof; a cap removably mounted on, and having a light-orifice in alignment with, the head-end of said casing; and a light-reflector carried by said cap and having a central aperture through which said socket extends when said reflector is in light-reflecting relation with a bulb in said socket in the mounted condition of said cap; of a light-permeable tube comprising telescoping tube sections of which the cross-sectionally largest and smallest tube sections are secured in the head-end of said casing and to said reflector, respectively, substantially coaxially of said casing and substantially concentrically with the aperture in said reflector, respectively, so that said tube will be extended from and contracted into the head-end of said casing on removing said cap from and mounting it on the head-end of said casing, respectively, said tube being in its extended condition in illuminating relation with a bulb in said socket, and said tube sections being marked to signify, when illuminated, an emergency signal.

8. The combination in a flashlight as set forth in claim 7, further comprising an auxiliary light-reflector having a central aperture through which said socket extends, said auxiliary reflector being yieldingly urged into light-reflecting relation with a bulb in said socket in the extended condition of said tube, and being depressed in said casing from light-reflecting relation with a bulb in said socket by sections of the contracted tube in the mounted condition of said cap.

9. In a light, the combination of a casing; a socket for a light bulb in said casing, said casing having an opening in illuminating relation with a bulb in said socket; a cap removably mounted on said casing in covering relation with said opening in the latter; and a light-permeable tube connected with said cap and said casing, and having provision for permitting said tube to be extended from and retracted into said casing through said opening therein on removing said cap from and mounting it on said casing, respectively, said tube being in its extended condition in illuminating relation with a bulb in said socket.

10. In an emergency light, the combination of a tubular battery-casing having an open head-end; a socket for an electric light bulb centrally in said casing adjacent said head-end thereof; a cap removably mounted on the head-end of said casing in covering relation therewith; and a light-permeable tube comprising telescoping tube sections of which the cross-sectionally largest and smallest tube sections are secured in the head-end of said casing coaxially thereof and to said cap, respectively, so that said tube will be extended from and contracted into the head-end of said casing on removing said cap from and

mounting it on the head-end of said casing, respectively, said tube being in its extended condition in illuminating relation with a bulb in said socket, and said tube sections being marked to signify, when illuminated, an emergency signal.

11. The combination in an emergency light as set forth in claim 10, in which said tube sections are red-colored and translucent and of frusto-conical shape, so that they simulate in their extended and illuminated condition a lighted torch. 10
